TELEMETRIC SYSTEM

Anthony J. Hornfeck, Lyndhurst, Ohio, assignor
to Bailey Meter Company, a corporation of
Delaware

Original application October 25, 1947, Serial No.
782,114, now Patent No. 2,524,665, dated Octo-
ber 3, 1950. Divided and this application April
22, 1950, Serial No. 157,555

7 Claims. (Cl. 177—351)

1

This invention relates to telemetric systems, and more particularly to systems for transmitting signals in response to a variable and positioning a receiving member by the signals at a remote point to provide an indication or record of the variable.

A preferred form of my invention may include a transmitting mechanism operating to produce a signal varying in response to a variable to be measured, and a receiving mechanism having a balanceable network which is subjected to different unbalancing conditions during intervals of time varying with the signals transmitted. The signal may be transmitted during portions of fixed time intervals to produce a condition tending to unbalance the network in one direction, and means may be provided to produce another condition tending to unbalance the network in the opposite direction during the remainder of the time intervals. If desired, the transmitter may produce different signals during the portions of the time intervals for creating different unbalancing conditions. The unbalancing effect on the network is proportional to the difference between the products of the unbalancing conditions and the intervals of time during which each is applied. Means responsive to an unbalance of the network may be provided for rebalancing the latter and for positioning suitable indicating or recording means.

An object of my invention is to provide an improved telemetric system. Another object is to provide a telemetric system having improved transmitting and receiving mechanisms. Yet another object is to provide a telemetric system which includes only a pair of wires between a transmitter and a receiver, and which operates to provide an indication or record at the receiver of a variable by the transmission of signals at low voltage over the pair of wires. Other objects will appear in the course of the following description.

The single figure of the drawing is a schematic diagram of an improved transmitting mechanism adapted for use in a telemetering system of the general type disclosed in my parent Patent No. 2,524,665 of which this application is a division.

The transmitter includes transformers 55 and 56 having primary windings 57 and 58 connected to a source of alternating current, and airing secondary windings 60, 61 and 62, 63 connected in a closed loop by conductors 64, 65. A core member 67 is arranged between the primary and secondary windings of the transformer 55 and is connected to one end of a pivoted member 68

which engages at its other end with a cam 69 rotated at a constant speed by a motor 70. The cam 69 is shaped so as to reciprocate the core member 67 at a constant speed between the windings of the transformer. Arranged between the primary and secondary windings of the transformer 56 is a core member 72 which is connected to a device 73, such as a Bourdon tube, responsive to some variable condition. Leading from the closed loop at points between the aiding secondary windings are conductors 74 and 75 connected to a phase sensitive relay 76 like that disclosed in my application, S. N. 633,891, filed December 8, 1945. This relay is of the electronic type and is operative at a very small voltage of a predetermined phase to move a contactor 78 into engagement with a contact 79 for completing the circuit through the conductors 17 and 18. The core member 72 may be considered as a transmitting member since the closing of contactor 78 to energize the conductors 17, 18 is determined by the position assumed by this member.

When the core members 67 and 72 are in the same positions with respect to the windings of their transformers, the voltages induced in the corresponding secondary windings are equal and opposite so that the voltage across the conductors 74, 75 is zero. If the core members are displaced from each other in one direction, a voltage of a certain phase exists across the conductors 74, 75, and the value of the voltage varies with the amount of displacement. When the core members are displaced in the opposite direction, a voltage opposite in phase to the first voltage exists across the conductors 74, 75. The range of reciprocation of the core member 67 should be adjusted so that its upper and lower limits are equal to or greater than the limits of the core member 72 on maximum changes in the condition to be measured. The range of the core member 67 may be determined by the size of the cam 69 and the location of the pivotal support for the member 68.

Assume that the core members are in the same positions with respect to the windings of their transformers and that the core member 72 remains in this position while the core member 67 is reciprocated. A very slight movement of the core member in one direction will produce a voltage of a phase which operates the relay 76 to close the contactor 78 with the contact 79. While the core member moves in this direction to the end of its stroke and then returns to its initial position, the voltage will continue to be of a phase to operate the relay. As soon as the core

member returns to its initial position the voltage across conductors 74, 75 becomes zero and the contactor 78 moves to its open position. A movement of the core member to the other side of its initial position results in a voltage opposite in phase to the first voltage, and the contactor 78 remains in its open position. If the core member 72 is in a position mid-way between the positions it would assume at the opposite limits of the condition measured, and if the core member 67 is reciprocated between corresponding limiting positions, the distances traveled by the core member 67 at opposite sides of the core 72 are equal and result in a holding of the contactor 78 open and closed equal intervals of time. A movement of the core member 72 from its mid-position means that the core member 67 must move an equal amount from such position to reach a point from which it may travel in either direction to produce voltages of different phase. Since the core member 67 will have a greater distance to travel in one direction than the other from its new position, the contactor 78 will be held open or closed longer intervals of time.

Whilst there is disclosed in this application one form which my invention may assume in practice it will be understood that it may be modified and embodied in various other forms without departing from its spirit or the scope of the appended claims.

This application is a division of my copending application S. N. 782,114, filed October 25, 1947, now Patent 2,524,665 dated October 3, 1950.

What I claim as new and desire to secure by United States Letters Patent is:

1. A mechanism for transmitting signals representative of a variable condition including in combination, a closed loop circuit including two pairs of secondary transformer windings, an energized primary winding for each pair of secondary windings, means for increasing the flux linkage between each primary and a secondary of each pair and to decrease the flux linkage with the other secondary of each pair to produce a net differential voltage across the two secondaries of each pair whose magnitude is a linear function of the movement of the flux linkage means, means for uniformly varying the linkage between one set of primary and secondary windings within predetermined limits, means for varying the linkage between the other set of primary and secondary windings in response to changes in the variable to be measured, a phase sensitive device connected to said closed loop at points between the two secondary windings of each included pair, and a circuit connected to a source of power and having a contactor controlled by said phase sensitive device.

2. A mechanism for transmitting signals representative of a variable condition including in combination, two transformers each having a primary winding and a pair of aiding secondary windings, means for energizing said primary windings, means for connecting said secondary windings in a closed loop, means for variably flux-coupling the primary and secondary windings of each of said transformers, means for uniformly varying the coupling between one set of primary and secondary windings within predetermined limits, means for varying the flux-coupling between the other set of primary and secondary windings in response to changes in the variable to be measured, a relay sensitive to the difference in output connected between the secondary windings of each of

5 said transformers, and a circuit controlled by said relay.

3. A mechanism for transmitting signals representative of a variable condition including in combination, two transformers each having a primary winding and a pair of aiding secondary windings, means for energizing said primary windings, means for connecting said secondary windings in a closed loop, a core member movable between the primary and secondary windings of each of said transformers, means for reciprocating one of said core members in a predetermined path, means for positioning the other of said core members in response to changes in a variable to be measured, a phase sensitive device connected to said closed loop at points between the two secondary windings of each of said transformers, and a circuit connected to a source of power and having a contactor controlled by said device.

20 4. A mechanism for transmitting signals representative of a variable condition comprising, in combination, two transformers, each having a primary winding and a pair of aiding secondary windings, means for connecting said primary windings to a source of alternating current, means for connecting said secondary windings in a closed loop, core members movable between the primary and secondary windings of said transformers, means for positioning one of said core members in response to a variable to be measured, means for reciprocating the other of said core members between points corresponding to the positions assumed by the first core member at extreme values of said variable, a phase sensitive 25 device connected to said closed loop at diametrically opposite points, and a circuit connected to a source of power and having a contactor movable to open and closed positions under the control of said device.

40 5. A mechanism for transmitting signals representative of a variable condition comprising, in combination, two transformers, each having a primary winding and a pair of aiding secondary windings, means for energizing said primary windings, means for connecting said secondary windings in a closed loop, core members movable between the primary and secondary windings of said transformers, means for reciprocating one of said core members in a predetermined path, means for positioning the other of said members in response to a variable to be measured, a phase sensitive relay connected to said closed loop at points between the secondary windings of each of said transformers, and a circuit connected to 45 a source of power and having a contactor movable to open and closed positions under the control of said relay.

6. A mechanism for transmitting signals representative of a variable condition including in combination, two transformers each having a primary winding and a pair of aiding secondary windings, means for energizing said primary windings, means for connecting said secondary windings in a closed loop, core members movable 50 between the primary and secondary windings, a cam operatively connected to one of said core members to move it in a predetermined path, a constant speed motor means for activating said cam uniformly that the core will reciprocate in the path, means for positioning the other of said members in response to a variable to be measured, a phase sensitive relay connected to said closed loop at points between the secondary windings of each of said transformers, and a circuit connected to a source of power having a contactor 55 70 75

movable to open and closed positions under the control of said relay.

7. A telemetric transmitter for transmitting an electrical signal varying in representation of a variable to be measured or transmitted, including in combination, two movable core transformers each having a primary winding and a pair of secondary windings and a core movable relative to the said windings for varying the flux linkage therebetween, a loop circuit including said secondary windings, a source of alternating current

for the primaries, means for cyclically positioning the core of one transformer between predetermined limits, means for positioning the core of the other transformer in accordance with the variable, a phase sensitive device connecting the joining point of each pair of secondaries in said loop circuit, and a relay controlled by the said device.
